WAISTBAND STRUCTURE FOR GARMENTS
Marvin Eppy, 28 St. Marks Place, New York, N.Y.
Filed Dec. 9, 1958, Ser. No. 779,153
7 Claims. (Cl. 2—236)

The present invention is directed to garments, more particularly to garments which have waistbands, such as trousers, slacks, skirts and the like. More specifically, the invention is directed to an improved structure of the waistband of such garments.

In the prior art, various structures of waistbands have been known but most of them have been for the purpose of offering support and confinement at the abdominal region. For instance, in a prior art structure the waistband of the garment was made considerably wider than the normal waistband and the series of vertical pockets were provided into which steel strips were inserted. Also, the waistband was provided with lacing in order to enable it to be tightened to firmly support the abdomen. This had a number of disadvantages in that it so confined the wearer that it was difficult for the wearer to bend without being subjected to pressure and pain from the ends of the steel members. Also, the structure was expensive and difficulties were encountered in the washing or other treatment of the garment.

In still another structure for the same purpose there was provided a waistband containing a metal chain in sinuous form which was permanently secured in the waistband. This in part overcame the disadvantages of the aforesaid prior structure in that some flexibility was obtained but it greatly stiffened the entire waistband and the other disadvantages of a stiffened wide waistband were inherent therein.

The present invention is directed to a structure of a waistband for a different purpose, namely to be incorporated in a garment of relatively thin and flexible material in order to sufficiently stiffen the front of the waistband so as to prevent the waistband from becoming creased in the normal wear thereof.

Therefore, it is among the objects of the present invention to provide a novel structure of waistband particularly for garments made of light weight fabrics which not only prevents creasing thereof while being worn but at the same time allows free movement of the body.

It is also among the objects of the present invention to provide a simple structure which is inexpensive and in which stiffening elements are readily removable in order to facilitate washing or cleaning of the garment.

It is further among the objects of the invention to provide as a stiffening member a thin strip of semi-flexible material, preferably of non-metallic materials, which provides a greater stiffness in the area of the centerline of the garment than the remaining areas of the waistband.

In practicing the present invention there is provided the usual waistband which may be of a number of layers of fabric sewn together. In accordance with the invention there is formed in the waistband and preferably to the back thereof a pair of horizontal pockets which extend laterally on each side of the front centerline thereof towards the sides of the garment. The pockets terminate short of the hip portion thereof. Into these pockets there are placed relatively thin but distortable strips of a synthetic resinous material and usually means are provided for retaining said strips against accidental displacement from the pockets.

In the preferred form of the invention each of the strips is folded longitudinally and placed in the pocket with the fold at the front of the garment. There is provided an opening in each pocket for the insertion of the strip which substantially fills the pocket so that prac-

2

tically no relative movement thereof with respect to the pocket is possible.

In the accompanying drawing constituting a part hereof and in which like reference characters indicate like parts:

FIGURE 1 is a fragmentary view of the interior portion of a waistband, some parts being broken away for clearance;

FIG. 2 is a transverse cross-sectional view taken along line 2—2 of FIG. 1;

FIG. 3 is a perspective view of a modified form of a pocket which is to be incorporated in a waistband;

FIG. 4 is an enlarged fragmentary horizontal cross-sectional view taken along line 4—4 of FIG. 3;

FIG. 5 is an elevational view, some parts being broken away, of a still further modified form of pocket;

FIG. 6 is an end view thereof taken along line 6—6 of FIG. 5;

FIG. 7 is a fragmentary perspective view of the preferred form of stiffening strip which is incorporated in the structure;

FIG. 8 is a schematic view showing the relationship between the waistband, the stiffeners and the pockets, and

FIG. 9 is a perspective view of a stiffener with a rounded end.

Referring to FIGS. 1 and 2, the garment 1 is provided with a waistband 2, the upper edge 3 of which is folded over as shown at 4 and stitched at 5 to form a pocket 6. A vertical slit 7 is provided at the front centerline 8 of the waistband and garment and a strip 9 of plastic material is inserted therein. As shown at 10 thereof the front end is bent and eased into the front of the pocket.

In FIG. 7 is shown the preferred form of strip 9 in which it is folded at 11 thereby providing legs 12 and 13 which are folded into contact with each other and inserted into the pocket with fold 11 being adjacent to the front centerline of the waistband. Various materials may be used for the strip, such as relatively thin sheets of vinyl resin or any other suitable plastic material. It is necessary that the strip be sufficiently thin so that it is readily bendable by even slight movements of the body of the wearer. However, it should be sufficiently stiff so that when the wearer is in erect position the strip holds the waistband smooth and free from creases. The fold 11 at the front of the garment gives a slightly added stiffness at a point where it is highly desirable in order to avoid distortion of the shape of the garment.

With reference to FIGS. 3 and 4, the pocket 14 is closed at the outer end 15 thereof and has an opening 16 at the front. A flap 17 having a snap fastener 18 is formed integral with the pocket and is adapted to be closed over pocket 14 in the direction shown by the line 19 and held in place by cooperating fastener 20. Strip 9 is inserted into the pocket prior to the closing and the pocket, itself, is stitched along its edges to the inside of the waistband.

Still another form of the invention is shown in FIGS. 5 and 6 wherein the pocket consists of a horizontal strip of fabric 21 which is folded at 22 so that portion 23 thereof forms a pocket 24 in which strip 9 is inserted. The lower end 25 is provided with snap fasteners 26 and is adapted to be folded over in the direction of arrow 27 to cooperate with fastener 28 and close the pocket.

While the invention has been described, setting forth several specific embodiments thereof, such forms are intended to illustrate the invention and not to limit it as many changes in the details may be made without departing from the spirit of the invention. For instance, in waistbands which are not open at the front, a single pocket may be provided in which either one or more stiffening strips may be inserted. The pockets may be formed in the central portion of the waistband or on the inner face

thereof. The openings for the insertion and removal of the strip may be formed in other places than those illustrated in the drawing and the form of the pocket may be different from those forms illustrated and described. Various means for retaining the strip against accidental displacement may be provided other than those shown.

These and other changes may be made within the spirit of the invention which is to be broadly construed and not to be limited except by the character of the claims appended hereto.

What is claimed is:

1. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, and an opening in each pocket for the insertion of said strip.

2. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, and an opening in each pocket for the insertion of said strip, the fold in each strip being adjacent to the centerline of said garment.

3. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, and an opening in each pocket for the insertion of said strip adjacent to said centerline.

4. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, an opening in each pocket for the insertion of said strip, and a flap on said pocket with fastening means for closing said opening.

5. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, an opening in each pocket for the insertion of said strip, and a flap on said pocket with fastening means for closing said opening, said flap being at one end of said pocket.

6. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, an opening in each pocket for the insertion of said strip, and a flap on said pocket with fastening means for closing said opening, said flap being along the lower edge of said pocket.

7. In a waistband for body garments having a front centerline and a pair of horizontal pockets extending on each side of said centerline toward but not beyond the sides of said garment, the improvement which comprises strips of relatively stiff, distortable plastic in said pockets, each of said strips being folded longitudinally and substantially filling each of said pockets, said fold being at the front of said garment, and an opening in each pocket for the insertion of said strip, the edges of said strip being rounded.
